DESIGN FOR A DISPLAY STAND

Harold C. Macpherson, San Francisco, Calif.

Application August 13, 1945, Serial No. 121,401

Term of patent 14 years

(Cl. D80—9)

To all whom it may concern:

Be it known that I, Harold C. Macpherson, a citizen of the United States, residing in the city and county of San Francisco, State of California, have invented a certain new, original, and ornamental Design for a Display Stand, of which the following is a specification, reference being had to the accompanying drawing.

I claim:

The ornamental design for a display stand, substantially as shown.

HAROLD C. MACPHERSON.
